V-BOTTOM BOAT

Peter G. Stamas, Tarpon Springs, Fla., assignor to Stamas
Boats, Inc., Tarpon Springs, Fla., a corporation of Florida

Filed Aug. 6, 1965, Ser. No. 86,483

Term of patent 14 years

(Cl. D71—1)

FIGURES 4 and 5 are rear and front elevational views respectively.

I claim:

The ornamental design for a V-bottom boat, substantially as shown.
